CALCULATING MACHINE

Edwin F. Britten, Jr., Short Hills, N. J., assignor
to Monroe Calculating Machine Company,
Orange, N. J., a corporation of Delaware

Application June 14, 1940, Serial No. 340,599

5 Claims. (Cl. 235—79)

The invention relates to calculating machines, and more particularly to means for controlling the registration devices of such machines in the solution of arithmetical problems such as division of an amount registered in the numeral wheels of the machine by an amount set up on the keyboard.

The invention consists in the novel construction and combinations of parts as hereinafter set forth in the claims.

In the accompanying drawings,

Figure 1 is a right side elevation of the machine, showing the invention as applied thereto, with the division key and the change lever in normal position, parts being broken away.

Figure 2 is a detail side view, showing the division key and the change lever in divide position, the movement transmitting means between said key and said lever and the manipulative means for restoring the change lever to normal position.

Figure 3 is a detail side view, showing the change lever in forward position and also in up position, and a portion of the movement transmitting means, parts being broken away.

Figure 4 is a left side elevation of the machine, showing the clutch for the reversible actuator driving train of gears, the division lever and a portion of said movement transmitting means, parts being broken away.

Figure 5 is a perspective view of the invention as applied, parts being broken away.

Figure 6 is a detail fragmentary longitudinal section of the change lever, showing the means for holding the adjustment of the slidable section thereof.

Figure 7 is a detail perspective view of the train of gears to the counter register, showing the clutch thereof and the connecting rod to the change lever, parts being broken away.

Figure 8 is a detail perspective view of the change lever.

In these drawings, the invention is shown as applied to a Monroe calculating machine, such for instance as disclosed in the U. S. patent to Overbury, No. 1,964,478, dated June 26, 1934, reference being made to the disclosure of the U. S. patent to Hilder, No. 2,160,361, dated May 30, 1939.

In accord with the disclosure of said patents, amounts set up on the keyboard are registered either once or repeatedly in the numeral wheels 13 mounted upon the shiftable carriage 2 upon operation of the machine through one or more cycles, and the number of cycles is registered in

5 the counting wheels 85, also mounted upon said carriage. Electrically operated motor drive mechanism for the machine is provided as disclosed in the U. S. patent to Chase, No. 1,566,650, dated December 22, 1925.

Also in accord with the disclosures of said patents, the machine is provided with differential actuators for the numeral wheels 13, and the motor drive mechanism of the machine includes 10 a reversible actuator driving train of gears having means including a clutch for effecting its reversal, a reversible carriage shifting train having right and left shift clutches and a reversible counter register train having means including a clutch for effecting its reversal. Control means includes a division key for controlling the clutch of the actuator driving train, the left shift clutch and the clutch of the counter register train.

Automatic division

The dividend having been registered in the numeral wheels 13 and the divisor set up on the keyboard of the machine, the division operation will be performed following setting of 25 the division key 201 to operative position. In this division operation the divisor is subtracted from the dividend until the registration becomes negative, a single corrective additive cycle is made, the carriage is shifted, and the computation repeated. The quotient is obtained by registering the net number of subtractions in the counter wheel 85.

The counter register is also capable of use as 30 a multiplier register in the solution of multiplication problems, in which case the multiplicand would be set up on the keyboard. In multiplication operations, registrations in the counter register 85 and in the numeral wheels 13 are of the same arithmetical sign, whereas in division operations such registrations are of unlike arithmetical sign, to effect which the counter register driving train is driven from the reversible drive means for said wheels 13 and is further provided with reversing means, including a clutch.

45 Thus the wheels 13 constitute a product-dividend register, and the wheels 85 constitute a multiplier-quotient register.

Heretofore and also in the present disclosure, the clutch for effecting the reversal of the counter register driving train is capable of manual control, and in the aforesaid Hilder patent means are provided for automatically controlling this clutch.

An object of the present invention is to render 50 a manipulative device or lever for such control

either settable or not settable by the division key, so that normally, the division key being set for a division operation, said device or lever will also be simultaneously set to divide position, whereas alternatively if said device or lever is not set by the division key, it is capable of independent setting to control said clutch, so that if desired the quotient may be registered complementally.

In order to carry out the invention there is provided movement transmitting means between the division key 201 and said manipulative device or lever, hereinafter termed the "change" lever, said movement transmitting means being effective for setting the change lever upon setting the division key and ineffective for restoring the change lever upon restoration of said key, and means carried by the change lever for presetting said movement transmitting means to ineffective or alternatively effective condition for setting said change lever upon setting the division key.

The change lever 3 has a rod 4 connecting the same with the clutch lever 5 for adjusting the clutch 6 of the counter register drive train of gears 1, said change lever being settable from normal forward position (Fig. 1) to rearward position (Fig. 2), in consequence of which in the operation of the machine the counter register wheels 85 will have the direction of their rotation reversed relative to the rotation of wheels 13.

The change lever is fulcrumed upon pin 8' in the stationary framing of the machine, and is provided with a slidable section 8, having upper and lower slot and pin connections 8, 8' with the main section, said slidable section having an upper handle extension and a lower pin 12. The change lever slidable section is adjustable from the "up" position of Fig. 3, to the "down" position of Fig. 1, as a consequence of which the pin 12 will be lowered therewith, whereas when the slidable section is adjusted from down to up position, said pin will be raised therewith.

In the setting of the change lever slidable section from up to down position, or alternatively from down to up position, the movement transmitting means between the division key and the change lever will be rendered effective or alternatively ineffective as aforesaid, by means now to be described.

The division key 201 has a rod 13' connecting the same with a rock lever 14 the lower arm of which has pivoted thereto at 15 the rear end of a member or link 16, which link in the up position of the slidable section of the change lever is supported forwardly upon the lower pin 12 of said section, the pin engaging a horizontally elongated notch 17 of said link and the upper edge of said notch contacting the pin. The forward end portion of said link is provided with an angular slot 18 wherein works a pin 19 of a cam 20, said cam being pivoted at 21 in the stationary framing, the pin 19 in the up position of said slidable section of the change lever being located in the angle of said slot (Fig. 3), and the cam having its upper edge 22 contacting the upper pin 8 of the slot and pin connection 8, 8'.

In the setting of the slidable section of the change lever from up to down position, the pin 12 thereof will be lowered therewith, which will permit the link 16 to fall by gravity until it comes to rest upon the aforesaid pin 19 of said cam, which latter pin will now be located at the upper end of the vertical branch of the angular slot 18 (Figs. 1 and 2), and upon which pin the link 16 will now be supported forwardly.

In this positioning of the parts, upon setting the division key from normal forward position to rearward operative or divide position the lever 14 will be rocked and link 16 will be moved rearwardly, thereby moving pin 19 and cam 20 and camming the change lever from normal forward to rearward or divide position (Fig. 2), where it will be held by the rear edge 23 of said cam, which edge is concentric with the cam pivot 21.

Thus the movement transmitting means between the division key and the change lever is rendered effective for the purpose stated upon setting of the slidable section of the change lever from up to down position and consequent pivotal movement or setting of the link or member 16 from up to down position.

In this movement of cam 20, a member 24 having at its forward end slot and pin pivotal connection 25 with a manipulative device or lever 26, and at its rear end portion supported by a lug 27 of said cam, will be raised pivotally by said lug, and at the end of the movement the hooked rear free end portion 28 of said member will be hooked partially around the upper pin 8 of the slot and pin connection of the two sections of the change lever (Fig. 2).

The manipulative device or lever 26 has one arm thereof provided with a coiled spring connection 29 with the forward end portion of said member 24, said spring being normally tensioned to hold the pin of the slot and pin connection 25 at the rear end of the slot, and in the movement of said member to the position stated, said spring will be further tensioned to maintain said member in said position.

Upon restoration of the division key to normal forward position, the link 16 will be returned forwardly and the cam 20 will also be returned to its first position, but the change lever will remain in rearward set position. The change lever can now be reset to normal forward position by manipulation of said device or lever 26, which may have other functions such as operation of keyboard clearing means functioning in the known manner.

In the setting of the change lever slidable section from down to up position, the pin 12 thereof will be raised therewith, thereby raising the link 16 pivotally until the lower edge of the angular slot 18 engages pin 19 of cam 20 to stop the upward movement, said pin 19 being now located in the angle of said slot and the link being supported forwardly upon the pin 12 of said slidable section.

In this positioning of the parts, upon setting the division key from normal forward to rearward or divide position, the lever 14 will be rocked and link 16 will be moved rearwardly as in the first instance, but the pin 19 being now located in the angle of slot 18 and the lower branch of said slot extending forwardly from said angle, the pin will move idly in the slot and there will be no consequent movement of cam 20 to set the change lever to divide position.

Thus the movement transmitting means between the division key and the change lever will be rendered ineffective for the purpose stated upon setting of the change lever slidable section from down to up position and consequent pivotal movement of the link 16 from down to up position.

Thus also, the link or member 16 may be switched from lower or "on" position (Fig. 2) wherein it is effective in transmitting movement to the cam 20, to raised or "off" position (Fig. 3)

wherein it is ineffective in transmitting movement to said cam, and back again to lowered position, and said member 16 constitutes a switch member of the movement transmitting means.

The change lever is capable of manual operation in the regular manner while the division key is in its normal forward position. However, when the change lever slidable section is set from up to down position and said lever is moved into divide position in the setting of the division key to divide position, said change lever is incapable of being reset to normal forward position either manually or by manipulative device or lever 26, until the division key is reset to normal forward position.

The downward movement of the cam 20 is limited by framing stop 30 (Fig. 3).

Suitable elastically yieldable means, such for instance as shown in Figure 6, is provided to maintain the slidable section of the change lever in its up and down positions. Suitable elastically yieldable means is also provided to maintain the division key in its normal and divide positions and the change lever in its normal forward and rearward set positions.

I claim:

1. In a calculating machine, having a product-dividend register, a multiplier-quotient register, and means including a division key for effecting alternate minus and plus registrations in the product-dividend register; reversing means including a manipulable device settable to render the multiplier-quotient register operative for registrations of a sign character like or alternatively unlike that of the other register, movement transmitting means between the division key and said device effective for setting the latter upon setting the former and ineffective for restoring said device upon restoring said key, and means for presetting said movement transmitting means to ineffective or alternatively effective condition for setting said device to render the one register operative for registrations of a sign character unlike that of the other register upon setting said key.

2. In a calculating machine, having a product-dividend register, a multiplier-quotient register, and means including a division key for effecting alternate minus and plus registrations in the product-dividend register, reversing means including a manipulable device settable to render the multiplier-quotient register operative for registrations of a sign character like or alternatively unlike that of the other register, movement transmitting means between the division key and said device effective for setting the latter upon setting the former and ineffective for restoring said device upon restoring said key, means for presetting said movement transmitting means to ineffective or alternatively effective condition for setting said device to render the one register operative for registrations of a sign character unlike that of the other register upon setting said key, and normally ineffective manipulable means for restoring said manipulable device, said movement transmitting means having a device for rendering said restoring means effective.

3. In a calculating machine, having a product-

dividend register, a multiplier-quotient register, and means including a division key for effecting alternate minus and plus registrations in the product-dividend register; reversing means including a manipulable device settable to render the multiplier-quotient register operative for registrations of a sign character like or alternatively unlike that of the other register, movement transmitting means between the division key and

5 said device effective for setting the latter upon setting the former and ineffective for restoring said device upon restoring said key including a switch member, and means for presetting said switch member and said movement transmitting

10 means to ineffective or alternatively effective condition for setting said device to render the one register operative for registrations of a sign character unlike that of the other register upon setting said key.

20 4. In a calculating machine, having a product-dividend register, a multiplier-quotient register, and means including a division key for effecting alternate minus and plus registrations in the product-dividend register; reversing means including a manipulable device settable to render the multiplier-quotient register operative for registrations of a sign character like or alternatively unlike that of the other register, movement transmitting means between the division key and

25 said device effective for setting the latter upon setting the former and ineffective for restoring said device upon restoring said key including a switch member, and means carried by said manipulable device and including a slidable handle

30 portion thereof for presetting said switch member and said movement transmitting means to ineffective or alternatively effective condition for setting said device to render the one register operative for registrations of a sign character unlike that of the other register upon setting said key.

35 5. In a calculating machine, having a product-dividend register, a multiplier-quotient register, and means including a division key for effecting alternate minus and plus registrations in the product-dividend register; reversing means including a manipulable device settable to render the multiplier-quotient register operative for registrations of a sign character like or alternatively unlike that of the other register, movement transmitting means between the division key and said device effective for setting the latter upon setting the former and ineffective for restoring said device upon restoring said key including a switch member, means carried by said manipulable device and including a slidable handle

45 portion thereof for presetting said switch member and said movement transmitting means to ineffective or alternatively effective condition for setting said device to render the one register operative for registrations of a sign character unlike that of the other register upon setting said key.

50 6. In a calculating machine, having a product-dividend register, a multiplier-quotient register, and means including a division key for effecting alternate minus and plus registrations in the product-dividend register; reversing means including a manipulable device settable to render the multiplier-quotient register operative for registrations of a sign character like or alternatively unlike that of the other register, movement transmitting means between the division key and said device effective for setting the latter upon setting the former and ineffective for restoring said device upon restoring said key including a switch member, means carried by said manipulable device and including a slidable handle

55 portion thereof for presetting said switch member and said movement transmitting means to ineffective or alternatively effective condition for setting said device to render the one register operative for registrations of a sign character unlike that of the other register upon setting said key, and normally ineffective manipulable means for restoring said manipulable device, said movement transmitting means having a device for rendering said restoring means effective.

EDWIN F. BRITTON, JR.
